Application December 27, 1956, Serial No. 630,899

6 Claims. (Cl. 122—225)

This invention relates to heating equipment, and more particularly to a boiler for hot water and steam.

In general this invention is concerned with improvements in the internal construction for boilers for obtaining increased efficiency in operation, and is applicable to smaller, for example domestic-size boilers, as well as to larger boilers as are used in heating plants for larger buildings. For purposes of describing a preferred form of the invention, however, it is shown embodied in a domestic size sectional type boiler, that is, a boiler unit made up of a plurality of individual inverted U-shaped sections which are fastened together by mechanical connecting devices and mounted on a base which accommodates a refractory combustion chamber.

Two primary features of internal construction of boilers govern boiler operation. These are (1) the ratio of direct and indirect heating surface, and (2) the character of flue gas travel through the boiler which is produced by the baffle and passage arrangement employed. The primary heating surfaces are those surfaces in the boiler exposed to the flame of combustion, while the secondary surfaces are all the remaining surfaces over which the hot flue gases travel.

It is a general object of the invention to provide an improved internal construction for boilers which obtains a more economical ratio of direct and indirect heating surface and a more efficient type of flue gas travel.

A primary advantage offered by sectional type boilers is that the same individual sections may be used in the erection of boilers of different sizes. It is a major object of the present invention to provide a sectional boiler offering better performance, lower draft loss, and higher over-all efficiency over a given series of different sizes, by reason of a new concept in boiler construction, namely, self-regulating flue gas travel. By controlling flue gas travel, even combustion is produced throughout the length of the boiler irrespective of the number of sections and the performance characteristics remain substantially the same for all boilers of a series.

It is an object of the invention to provide means for insuring that all boiler sections of a sectional boiler contribute equally in the transfer of heat to the heating surfaces by controlling flow of flue gases in a pattern such as provides optimum heat transfer. Another object is to provide a boiler where the boiler internally is uninterrupted by flue gas baffles, and where the natural draft is employed to force the flue gases to the heating surfaces at the sides of the boiler, and then to a central horizontal flue gallery which leads the flue gases to the chimney, and thus into wiping contact with a greater area of water-backed heating surface.

Another object of the invention is to provide a new and improved sectional boiler, the construction of which facilitates erection, operation and maintenance. A related object is to provide a sectional boiler construction which may be more readily dismantled. More specifically, it is an object to provide an improved means for sealing between adjacent boiler sections and one which

2

remains intact when the boiler sections are separated so as to be available to reseal the boiler when the sections are rejoined together, after repair or cleaning has been accomplished. It is another related object to provide sealing means employing an asbestos rope between boiler sections and where the rope is received in such a manner as to cause it to more effectively seal the boiler when the sections are assembled.

An additional object of the invention is to provide means for more readily gaining access to the internal passages of the boiler, when the sectional boiler is assembled. A related object is to provide such access by cleanout openings arranged between adjacent sections of the boiler and closed by means of removable cleanout plates. It is a further and a related object to provide means for securely locking the cleanout plates in position in the boiler.

Other objects will appear from the following description taken in connection with the accompanying drawings, wherein:

Figure 1 is a perspective view of a partially erected sectional-type boiler embodying this invention, with parts broken away to illustrate the internal constructional details of the boiler;

Fig. 2 is a sectional view, taken in the offset planes of lines 2—2 of Figure 1, and illustrates the internal construction of the boiler of Figure 1, with the center part of the boiler broken away and the front and back sections in place;

Figs. 3, 4 and 5 are front elevation views of the front, intermediate and back sections, respectively, of the boiler illustrated in Figs. 1 and 2;

Fig. 6 is a sectional view of the boiler of Figs. 1 and 2 taken in the plane of line 6—6 of Fig. 2;

Fig. 7 is a sectional view of this boiler taken in the plane of line 7—7 of Fig. 2;

Fig. 8 is an enlarged sectional view taken in the plane of lines 8—8 of Fig. 7, and illustrates the sealing means employed for sealing between adjacent sections of the boiler;

Fig. 9 is a fragmentary section taken in the plane of lines 9—9 of Fig. 2, and illustrating a mounted cleanout plate; and

Fig. 10 is a fragmentary section taken in the plane of lines 10—10 of Fig. 9, and again illustrating the construction of the cleanout plate and locking means therefor.

While the invention is susceptible of various modifications and alternative constructions, there is shown in the drawings and will be herein described in detail a preferred embodiment of the invention. It is to be understood, however, that it is not thereby intended to limit the invention to the specific form disclosed, but, on the contrary, it is intended to cover all modifications, alternative constructions and equivalents falling within the spirit and scope of the invention as expressed in the appended claims.

Turning now to the drawings, Figure 1 illustrates a sectional-type boiler, with the front section removed, designated with the general reference numeral 10, in which the present invention is incorporated. It is recognized that sectional boilers have been known heretofore, and in general boilers of this type embody U-shaped sections 11 erected on a base accommodating a refractory firebox 12, and provided as illustrated in Figure 1, to mount a burner in place on the front of the boiler. Hot flue gases are produced by flame in the firebox, and pass through the boiler to a smoke collar 14 (Fig. 2) which serves to lead the gases to the chimney. The smoke collar is fastened on the back section and receives flue gases from a collector constructed as horizontal flue galleries 15, the collector being in communication with the smoke collar through

the smoke opening in the outer wall of the back section casting.

As stated hereinbefore, the present invention introduces the new concept of self-regulating flue gas travel. By controlling the travel of hot flue gases through the boiler, optimum heat transfer to the primary and secondary heating surfaces may be obtained, and as well, the hot gases may be forced into wiping contact with a greater area of water-backed surface. Water for the generation of steam, or to be heated for supply to a hot water system, circulates through an internal header 16 (Figure 1) and through water passages 17 formed by coring the castings for each boiler section. As will be observed from a careful examination of Figure 1, the individual sections of the boiler are cast so as to form the water passages 17 within each individual section. The internal header 16 is formed by connecting the upper nipple openings 18 by slip nipples 19, and a pipe 20 connected to the header extends to the heating system. The boiler sections also are so constructed as to provide passages 21 for flue gas between each boiler section. For this purpose each side of the individual boiler sections is formed so that when the sections are connected together vertical uptake passages 21 are left between each section at both sides of the boiler, leading to the horizontal flue galleries 15 centrally of the boiler which communicates with the smoke collar and the chimney.

For transferring heat to the water circulating through the header 16 and the water passages 17 in the sections of the boiler, the flue gases in the firebox by natural draft created from the chimney, are forced laterally towards the outer wall of the boiler to pass upwardly between the individual boiler sections through the vertical uptake passages 21. Being formed between adjacent boiler sections, these uptake passages, as will be seen in Figure 1, open in their lower part to the arched region of the finned firebox crown 22. The vertical limits of the uptake passages 21 are defined by the rounded upper corners of the boiler itself, which form turn-around passages 21' and these passages 21' are disposed laterally of the horizontal flue gas galleries 15 with which the uptakes 21 communicate and into which the hot flue gases pass via the turn-around passages after flowing through the vertical uptakes. Since at each side and between every section of the boiler, a vertical uptake is formed, the hot flue gases in the firebox are divided into a plurality, the number being determined by the number of sections, of individual streams of gases, and these streams of gases flow into the horizontal flue galleries 15. For a purpose to be later described, certain of the uptakes 21 are of somewhat larger cross-sectional area than the others. The difference in area which is present, however, does not result in a substantial difference in resistance to flow of flue gas as between the different size uptakes. Therefore, each of the uptakes of the boiler receives a substantially equal share of the total volume of the flue gas produced in the combustion chamber.

To force the flue gases into a greater number of water-backed passages, the collector through which the gases pass in their travel to the chimney, in the present instance is divided into four spaced and parallel flue galleries 15 by centrally arranged hollow, vertical and horizontal webs 25, 26 forming additional water passages 27 to promote the circulation of water and to provide additional heating surface 28. In order to force the gases as they travel towards the back of the boiler into the lower pair 29, 30 of flue gallery passages, as seen in Figure 1, the cross-sectional area of these passages is made somewhat larger in size than the cross-sectional area of the upper pair 31, 32 of horizontal flue gas passages making up the central flue galleries 15 extending towards the back of the boiler. This arrangement embodying dividing the collector into parallel passages or galleries 15 and forcing the flue gases into the lower passages, contributes towards

obtaining balanced horizontal flue travel equalizing the heat absorption of secondary heating surfaces.

As a further means for obtaining balanced flue travel and equalized heat absorption throughout the entire length of the boiler, selectively certain of the vertical uptake passages of the boiler are enlarged in cross-section. In the present arrangement, and as exemplary only, the vertical uptakes 39 formed between the front end section 40 (Fig. 2) and the adjacent intermediate section 41 are made larger than the uptakes 21 between the other sections of the boiler. The effect of the larger cross-section for the uptake pair 39 at the sides of the boiler in the region of the firing, is to force a greater portion of the flue gases produced in the firebox through these 15 larger area uptakes. Natural draft drawing flue gases from the firebox to the chimney, would ordinarily tend to short circuit those flue gas passages at the front end of the boiler, and by enlarging the uptake area and reducing the friction loss, the draft through the boiler has the effect of 20 forcing the flue gases through those uptakes into regions of the boiler which without such a provision would receive a lower volume of flue gases. A further feature contributing to balanced flue gas travel is obtained as a result of forming the uptakes 21 regular in cross-section, 25 as shown in Fig. 2, and employing the turn-around passages 21', which introduce greater resistance to flue gas flow than is offered by the uninterrupted uptake passages. Moreover, by tapering the uptakes 21, as shown in Figs. 3-5, from a larger cross-sectional area at 21" where the 30 uptakes 21 open into the combustion chamber, the velocity of the flue gas remains uniform the length of the uptakes, notwithstanding the temperature drop of the gas occurring as it passes through the uptake, thus obtaining uniform heat transfer.

35 Enlarging the uptake area adjacent the front end section of the boiler shown as exemplary in the drawings of this application, adds an additional important effect, namely obtaining substantially uniform boiler performance for all boiler sizes of a series. This aspect of the 40 invention may best be explained by reference to an actual example of boiler construction, a boiler designed for a larger type residence and for firing by an oil burner. As has been set forth above, different size boilers made of the same boiler sections may be erected by using a 45 different number of like intermediate sections with the same front section and back section. In theory, by means of the present invention, boiler performance would be substantially uniform irrespective of the number of sections employed in the boiler. For example, from a four section boiler to the largest of a series including an infinite number of sections. As a practical matter, however, there is a limit to boiler length, and from that standpoint and from others such as ease in erection, it is preferred and contemplated that several series of boiler sizes 50 will be provided. Of course, in each series only are the various front, back and intermediate boiler sections the same. While there would be some overlap between the largest boiler in the series to the smallest boiler of the next larger series, as the boiler sizes increase the over-all 55 dimensions may become larger so that all the dimensions of the erected unit are kept within reasonable limits. In the present instance, the smallest boiler size within a series would be made of four sections, the largest size, although more sections could be employed, of eight sections. The middle sizes may be obtained by adding intermediate sections, two only being used for the smallest, three for the next larger, up to the six intermediate sections required for the largest size boiler. In each case the front section and back section would be 60 the same, and in the chosen illustrative example, the front 40 and back 43 sections of Figs. 3 and 5 respectively, would be employed in the boiler. The intermediate section 41 shown in Fig. 4, similarly, would be employed in the illustrative example of the present invention. The smallest boiler, of course, has the smallest 65 70 75

capacity and output while the largest boiler has the largest output.

In the present example of a boiler series, chosen to illustrate this aspect of the invention, measured in terms of actual fuel input (oil), the smallest boiler of the series has this input:

4-section boiler—2.25 gals. per hour while the largest boiler of the series:

8-section boiler—4.10 gals. per hour.

The above figures are actual test figures and reflect a non-linearity in input, and a corresponding drop over the boiler sizes of the series in the input of fuel and likewise in the volume of flue gases produced. It will be appreciated that the production of hot flue gases, the medium for heating water in the boiler, is in direct proportion to the amount of fuel burned. This drop over the whole series may be computed as follows:

$$\begin{array}{r}
 2 \times 2.25 \text{ gals. per hr.} = 4.50 \\
 \text{Actual input} \quad \quad \quad = 4.10 \\
 \hline
 \quad \quad \quad .40 = 8.8 \\
 \hline
 \quad \quad \quad 4.50
 \end{array}$$

(Note.—Twice the input for four sections, if the relation is linear, would give the input for eight section unit.)

As described hereinbefore, the total volume of flue gases produced in the firebox is divided by the large number of vertical uptakes between the boiler sections into a like number of streams of gases. When dealing with different boiler sizes, in order to obtain uniform boiler performance, it is necessary that the velocity of the flue gases flowing through the vertical uptakes of the small boiler in the series, for example, the four-section boiler above, be maintained substantially the same as the velocity of flue gases flowing through the uptakes of the largest boiler in the series, as for example the eight-section boiler above.

For obtaining substantially uniform velocity of flue gases for all boiler sizes of a given series, in the present instance, and as an exemplary form of the invention, the cross-sectional area of the vertical uptakes 39 between one of the end sections 40 and the adjacent intermediate section 41 to it, is made larger than the cross-sectional area of the other vertical uptakes 21. The larger size uptakes 39 should be at the end of the boiler opposite to the smoke outlet opening, and in the boiler as illustrated in the drawings of this application, would be in the region of the firing of the boiler. Whether the larger uptakes are in the front section or in the back section of the boiler, therefore, depends upon whether the boiler is front or back fired, and upon the location of the smoke outlet opening, i.e., whether it is in the back or the front of the boiler. Referring to the following further data on the example chosen to illustrate this aspect of the invention:

Cross-sectional area:

Uptakes in front section: 9 sq. in.

Uptakes in other sections: 6 sq. in.

4 section boiler total=42 sq. in.

$$2 \times 9 = 18 \text{ sq. in.}$$

$$4 \times 6 = 24 \text{ sq. in.}$$

$$42 \text{ sq. in.}$$

8 section boiler total=90 sq. in.

$$2 \times 9 = 18 \text{ sq. in.}$$

$$12 \times 6 = 72 \text{ sq. in.}$$

$$90 \text{ sq. in.}$$

For equal size uptakes between the sections of a four section boiler, in order to obtain the same total cross-sectional area, each uptake would be required to be 7 sq. in. in size.

8 section boiler total with equal (7") size uptakes=98 sq. in.

With selectively different size uptakes the actual total uptake area=90 sq. in.

Percentagewise this difference:

$$\begin{array}{r}
 98 - 90 = 8 \text{ sq. in.} \\
 8 = 8.1\% \\
 \hline
 98
 \end{array}$$

As described and computed above, the actual drop in input over the series of from four to eight sections of the boiler of the chosen example, is 8.8%. The 8% less cross-sectional area of the uptakes of the eight section boiler substantially matches the non-linearity in input. Consequently the velocity of flue gases in the largest boiler size is maintained substantially the same as the velocity of flue gases in the smallest boiler size in the series. As will be clear to a man skilled in the art, the same holds true for the intermediate sizes and thus boiler performance is made uniform from this standpoint over the entire series.

In general mathematical terms, the relation between the total uptake area and the area of the individual uptakes may be expressed as follows:

$$y=ax+b$$

where

y=total uptake area

a=area of individual uptakes

x=number of intermediate sections

b=fixed uptake area at front and rear sections

It will be readily appreciated there are other factors contributing to boiler performance which may be non-linear as the boiler sizes vary, however, by compensating for the major non-linear factor, substantially uniform performance may be obtained from the same section (front, intermediate, and back) sold to be erected into different boiler sizes.

In the erection of the boiler shown as exemplary in the drawings, taking for illustration the four section unit of Fig. 2, the front section 40 is first placed on top of a rectangular, usually cast-iron, base 45 and a slip nipple 19 is installed in the upper slip nipple opening 18 to form the internal header 16. Before adding another section, it is also necessary to clean the smaller, lower nipple openings 46 for receipt of the lower nipples 47 which are pounded in place to form part of the water passage system of the boiler. As will be seen from Fig. 3, which illustrates the front section 40 of the boiler in elevation, this section is cast with lands 50 around the outer edge and also centrally 51 about the collector, which collector in the present instance is constructed as parallel passages leading towards the smoke outlet opening at the back of the boiler. These lands 50, 51 meet similarly formed lands 52, 53 on the intermediate section 41 adjacent to the front section, for example the intermediate section shown in Fig. 4, and form the outer wall 54 of the erected boiler and also define the collector passages (15) internally of the boiler.

For sealing between meeting lands on adjacent sections 60 of the boiler, and thus for sealing between every section of the boiler, the lands are grooved or channeled for receiving sealing material. In the present instance heat resistant flexible rope such as asbestos rope 55 is used for the sealing material. In the erection of the boiler 65 this rope is draped around the outer wall 54 of the boiler and laid in the grooves or channels 56 found in the lands 50 there. Similarly, centrally of the section about the collector, asbestos rope is laid in the groove 57 of the land 51 forming a U. It is preferred that the asbestos rope should be spot-glued 58 in place in the (Fig. 8) curved sealing grooves, using adhesive. As will be readily appreciated, this also facilitates erection of the boiler because the asbestos rope is held in place. So that the sealing material may remain intact upon dismantling of the boiler, the adhesive should be applied

only to one side of the asbestos rope in the grooved lands of one section of the boiler. After the asbestos rope has been placed on the front section, the upper and lower nipple openings of an intermediate section 41 are then prepared for receiving the nipple, and this section (Fig. 4) is placed on the base 45. This intermediate section 41 is then driven against the front section 40 with a heavy mallet or the like to start the nipples into the lower openings and into the upper ports or openings of that section. At this point, the draw rods 59 are assembled on the sides of the boilers and the intermediate section is then connected by means of these draw rods to the front section 40.

The remaining sections are then assembled in place following the same sequence of steps. In a four section boiler, for example, another intermediate section is erected and then a back section 43 like that shown in Fig. 5 is installed in the same manner as the front section 40 and the first intermediate section 41.

For insuring a perfect seal between boiler sections, the grooved or channelled lands 50, 52 forming the outer wall 54 of the boiler are fashioned so that during the operation of drawing the adjacent sections of the boiler together by means of the draw rods, the asbestos rope 55 in the outer curved sealing groove is compressed so as to form a relatively denser flue gas impervious bead towards the inside of the boiler. For this purpose, according to the present invention, the meeting lands 50, 52 are so formed that when the boiler sections are drawn fully together, to the position shown in Fig. 8, the gap 60 separating the inside edges 61, 62 of the boiler section outer wall 54 is smaller than the gap 63 separating the outside edges 64, 65 of the outer wall. The draw rods 59 when drawing the adjacent boiler sections together act to compress the asbestos rope 55 and actually extrude it into the gaps 60, 63 separating the sections to each side of the sealing rope. By providing a larger space towards the outside edge of the outer wall of the sections, however, the compressed asbestos rope is allowed to escape somewhat, providing compression relief, while the portion of asbestos rope towards the inside of the boiler is made denser and gas impervious. While the configuration chosen to illustrate this aspect of the invention is specific in its detail, modifications will be obvious to a man skilled in the art.

After the remaining sections are drawn into place by means of the draw rods 59, the lower nipple ports 46 around the top of the base 45 must be sealed with asbestos cement.

In the erection of the sections, when the sealing asbestos rope 55 is laid in the sealing groove 50, 52 along the outer wall 54 of the boiler, the rope 55 is laid to extend across cleanout openings 70 which are formed in the outer wall of the boiler on the top of the sections. These cleanout openings 70 are formed by opposed rectangular-shaped cutout portions 71, 72 cast in the sections which together, as shown in Fig. 2, form a cleanout opening between adjacent boiler sections. According to the present invention, these cleanout openings are provided with a removable plate 73 for closing the same. Referring to Figs. 2, 9 and 10, the boiler sections are cast with locking lugs 74, 75 along the opposite sides of the cutout portions 71, 72 forming the cleanout openings 70. These locking lugs slope from side to side of the boiler, and the opposite lugs together form part of a screw thread for receipt of a locking element 76 fastened to the plate employed for closing the cleanout openings. As shown in Figs. 9 and 10, the cleanout plate 73 has a raised bead 77 which extends into the cleanout opening to form a better seal, and centrally of the plate carries the depending locking element, consisting, as shown, of oppositely facing arms 78, 79 slightly twisted to engage the undersurfaces of the opposite locking lugs 74, 75. The lock element 76 is mounted on a pin or shaft 80 which is accessible by means of a hex cap 81 or the like on the top of the plate. To lock the plate

10

15

20

25

30

35

40

45

50

55

60

65

70

in place, the plate is lowered with the arms of the element 76 used for locking the plate in place pivoted so as to pass without contact the locking lugs on the opposite edges of the cleanout opening. The element is then turned, when the plate is in place, by means of the hex cap and a wrench, until the arms engage the undersurface of the locking lugs to hold the plate in place.

These cleanout openings 70 provide access to both the vertical uptakes 21 and the centrally located collector and the horizontal flue galleries 15 thereof within the boiler. This may be observed from an examination of Figs. 3-5 which reveal that the cleanout opening 70 is located in the present instance, at the upper termini of the uptakes 21 and slightly towards the center line of the boiler on the axis of these uptakes, so that the cleaning implement may be inserted through the cleanout openings and will reach into the uptakes to clean the walls or flue gas passage surface which may become covered with sooty deposits. The same is true of the horizontal flue galleries of the collector located centrally of the boiler, for access is provided to this region by means of the cleanout openings.

I claim as my invention:

1. In a sectional boiler having a plurality of spaced sections, means providing opposed channels in the facing edges of the adjacent boiler sections, and heat resistant flexible rope confined in said channels and sealing the sections of the boiler, said rope being sized such that when undeformed it is radially larger than the opening formed by the opposed channels, means for tying said sections together so that said rope is radially compressed, the edges of said sections being formed to leave a larger gap between said sections outwardly of said channels, said rope when so compressed forming a denser portion towards the inside wall of the boiler, the larger gap affording relief allowing said rope to squeeze towards the outside wall of the boiler.

2. In a sectional boiler having a plurality of spaced sections, means providing opposed channels in the facing edges of the adjacent boiler sections, heat resistant flexible asbestos rope confined in said channels, the edges of said sections being formed to leave a larger gap between said sections outwardly of said channels than inwardly of said channels, and means for tying said sections together, said latter means being effective for compressing said rope in said channels, said rope when so compressed forming a relatively denser gas impervious bead running along the inside wall of the boiler, the larger gap affording relief allowing said rope to squeeze outwardly between the edges of the boiler sections toward the outside wall of the boiler, for sealing between sections of the boiler.

3. In a boiler adapted to be erected on a fire box and formed to define, when so erected, a combustion chamber over the fire box, the combination comprising, fully enclosed water-backed uptakes extending from said combustion chamber vertically for receiving substantially equal shares of the gas produced in the combustion chamber, said uptakes being regular in cross-section and extending uninterruptedly from the combustion chamber to the top of the boiler, and a horizontal collector extending the length of the boiler located centrally thereof and below the upper termini of said uptakes for receiving the streams of flue gas from the uptakes, means providing a turn-around passage at the upper part of each of the uptakes through which the flue gas flows to said collector, each uptake being tapered from a larger cross-sectional area at the mouth thereof where the uptake opens into the combustion chamber, so that the velocity of the flue gas remains uniform the length of the uptake, said turn-around passage introducing substantially greater resistance to flue gas flow than is offered by the enclosed, regular, vertical uptake passage leading from the combustion chamber.

4. In a sectional boiler having a front end section, a back end section, a predetermined number of like intermediate sections, the sections being adapted to be erected on a fire box, said sections being formed to define,

when so erected, a combustion chamber over the fire box, the combination comprising, fully enclosed water-backed uptakes extending from said combustion chamber vertically between each of the boiler sections at the sides of the boiler for receiving substantially equal shares of the gas produced in the combustion chamber, said uptakes being regular in cross-section and extending uninterruptedly from the combustion chamber at the top of the sections, and a horizontal collector extending the length of the boiler located centrally thereof and below the upper termini of said uptakes for receiving the streams of flue gas from the uptakes, means providing a turn-around passage at the upper part of each of the uptakes through which the flue gas flows to said collector, each uptake being tapered from a larger cross-sectional area at the mouth thereof where the uptake opens into the combustion chamber, so that the velocity of flue gas remains uniform the length of the uptake, said turn-around passage introducing substantially greater resistance to flue gas flow than is offered by the enclosed, regular, vertical uptake leading from the combustion chamber.

5. In a sectional boiler having a plurality of separate sections erected on a fire box and defining a combustion chamber over the fire box, the combination comprising, means providing passages in the boiler sections and primary and secondary heating surfaces for heat transfer to water in said passages from the flue gas produced in the combustion chamber, uptakes defined between each of the boiler sections at the sides of the boiler for receiving the flue gas produced in the combustion chamber, a portion of said primary heating surface being provided by the lower regions of said uptakes, a portion of said secondary heating surface being provided by the upper regions of said uptakes, and a collector located centrally of the boiler and below the upper termini of said uptakes and extending the length of the boiler, for receiving the flue gas from the uptakes, means providing a turn-around passage at the top of each of the uptakes through which the flue gas flows to said collector, said uptakes being regular in cross-section and providing a continuous, uninterrupted path through which the flue gas flows to the collector, said turn-around passages introducing substantially greater resistance to flow of flue gas than is offered by the regular, vertical uptakes, the flue gas from the combustion chamber being substantially divided between the uptakes of the boiler by the greater resistance to flow of said turn-around passages, said collector comprising a plurality of horizontal galleries providing the

remaining portion of said secondary heating surface, the lower and outer of said galleries having a larger cross-sectional area than the upper and inner of said galleries for drawing the flue gas uniformly over said secondary heating surface.

6. In a boiler adapted to be erected on a fire box, and formed to define, when so erected, a combustion chamber over the fire box, the combination comprising, water-backed uptakes extending from said combustion chamber uninterruptedly vertically to the top of the boiler, said uptakes being regular in cross-section and providing primary and secondary heating surfaces, and vertically separated water-backed horizontal galleries extending centrally of the boiler and below the upper termini of said uptakes, for receiving flue gas therefrom, means providing a turn-around passage at the upper part of each of the uptakes through which the flue gas flows to said collector, each said vertical uptake being tapered from a larger area at the mouth thereof where the uptake opens into the combustion chamber so as to provide a relatively greater primary heating surface and so that the velocity of the flue gas remains substantially uniform the length of said uptake, said turn-around passage introducing substantially greater resistance to the flue gas flow than is offered by the vertical uptake so that each uptake receives a substantially equal share of the flue gas produced in the combustion chamber, thereby to obtain uniform distribution of flue gas over the secondary heating surface provided by the uptakes, said galleries providing additional secondary heating surface, the lower of said galleries having a larger cross-sectional area than the upper thereof for drawing a portion of the flue gas downwardly into the lower gallery, so that a uniform distribution of flue gas is obtained.
